UNITED STATES PATENT OFFICE.

ELDON W. BALDWIN, OF NAMPA, IDAHO, ASSIGNOR OF ONE-HALF TO JOHN C. SEWELL, OF NAMPA, IDAHO.

SWIVEL FOR LIGHT AND DROP CORDS AND THE LIKE.

Application filed April 2, 1926. Serial No. 99,397.

The present invention has for its purpose to provide, in a swivel fixture for light and drop cords and conductors to other electrical devices, a construction of two sections forming the swivel, with means for swivelly uniting the two sections, thereby preventing the cord from twisting and winding up, more especially should the cord be of great extent in length.

10 Another purpose is to provide means for fastening the wires of the cord to the two sections of the swivel, the two sections consisting of insulating material, with imbedded conducting means therein for insuring the 15 conduction of electric current.

Still another purpose is to provide anti-frictional means between the two sections of the swivel, to allow the two sections to freely move.

20 A further purpose is to provide yieldable contacts between the two sections of the swivel, certain of the contacts being in the form of a circular ring, so that when the sections relatively swivel, the contacts remain 25 engaged at all times.

A further purpose is a provision and means for permitting two, three or four wires to be connected to the sections of the swivel, and yet permit the sections to swivel relatively to 30 each other.

It is to be understood that the particulars herein given are in no way limitative and that while still keeping within the scope of the invention, any desired modifications of detail 35 and desired proportions may be made in the apparatus according to circumstances.

The invention comprises further features and the combination of parts, as will be hereinafter set forth, shown in the drawings 40 and claimed.

In the drawings:—

Figure 1 is a view in elevation of an electric light drop cord, showing the improved swivel connecting the two sections of the cord. 45 Figure 2 is an enlarged detail sectional view through the swivel.

Figure 3 is a plan end view of one of the sections of the swivel, showing the yieldably mounted contacts.

Figure 4 is an end plan view on the other

section of the swivel, showing the circular contact ring, and the center stationary contact.

Figure 5 is a cross-sectional view on line 5—5 of Figure 2.

Figure 6 is an enlarged sectional view on a modified form of swivel, wherein the anti-frictional means are yieldably mounted, and wherein the yieldable contacts are eliminated.

Figure 7 is a sectional view on line 7—7 of Figure 6.

Figure 8 is a detail view showing the swivel as mounted on a screw plug.

Figure 9 is a view in elevation of the swivel as mounted on a push plug.

Figure 10 is an end plan view of one section of the swivel, showing three circular contact rings in addition to the center stationary contact, so that four conductors or 70 leads may be connected to each section of the swivel, and thereby prevent the entanglement of the cord.

Referring to the drawings, more especially Figure 1, 1 denotes an electric fixture comprising a drop cord and the usual drop light or bulb 2. The drop cord comprises the two sections 3 and 4, the latter carrying the drop light or bulb, the former depending from the ceiling or other suitable location. The two sections of the drop cord are connected by the improved swivel 5, which consists of the two sections 6 and 7. These sections are constructed of any suitable insulating material, preferably porcelain or the like, and cast 85 or formed in the section 6 are conductors 8 and 9 provided with sockets 10 and 11, designed to receive plugs or terminals (not shown) to be carried by the two wires 12 and 13, which are encased in the section 3 of the drop cord. Suitable set screws 14 and 15 are threaded transversely of the section 6 of the swivel and through the portions of the walls of the conductors 8 and 9, partly adjacent to and into the sockets 10 and 11. 90 The heads of the set screws are countersunk in the section 6, while the ends of the shanks of the set screws are designed to bear against the plugs (not shown) carried by the wire 12 and 13, for the purpose of securing 100

95

the plugs in the sockets and insuring proper electrical connections.

Formed or encased in the section 7 are conductors 16 and 17, likewise provided with 5 sockets 18 and 19, for the reception of plugs (not shown) carried by the wires or leads 20 and 21 which are encased in the section 4 of the drop cord. Suitable set screws 22 and 23 extend transversely of the section 7 of 10 the swivel and through the wall of the conductors 16 and 17, the purpose of which being to retain the conductors 16 and 17 in 15 position, as well as engaging with and holding plugs (not shown) in the sockets 18 and 19.

The porcelain section 6 of the swivel has a socket 24, which receives a tubular extension 25 of the porcelain section 7. The conductor 17 extends through the extension 25 and terminates in a flat contact head 26. The conductor 16 terminates in a flat circular contact ring 27, which lies against the face 28 of the porcelain section 7.

The conductors 8 and 9 have sockets 29 and 25 30 for the reception of contact pins 31 and 32. Upon inspection of Figure 2 of the drawing it will be noted that the conductor 9 terminates in the bottom of the socket 24, therefore the nose of the contact pin 32 projects 30 into the socket 24 and is in axial alignment with the conductor 17.

The socket 29 of the conductor 8 aligns axially with the center of the conductor 16, and its nose protrudes in order to ride against 35 the face of the contact ring 27. Suitable coil expansion springs 33 and 34 are mounted in the sockets 29 and 30 to insure a yielding action for the pins, the contact pin 32 engaging with the contact head of the conductor 17.

40 Obviously, as long as the two adjacent ends of the sections 6 and 7 of the swivel are positioned as shown in Figure 2 to enable the pins 31 and 32 to contact with the ring and the head, electrical connections between the conductors in the two sections of the drop cord are afforded. Furthermore, the two sections 45 of the swivel are permitted to have freedom of movement swivelly.

To insure the swivel action the two sections 50 6 and 7 have shoulders 35 and 36 provided with runways 37 and 38, which are engaged by anti-frictional ball bearings 39 and 40. These ball bearings are carried in conventional retaining rings 41 and 42. For the 55 purpose of holding the retaining rings 41 and 42 in position carrying the anti-frictional ball bearings, suitable sleeves 43 and 44 are provided. These sleeves telescope the adjacent end portions of the two sections 6 and 7 of the 60 swivel, and have annular flanges 45 and 46 which engage with and retain the rings 41 and 42 in position. The sleeves 43 and 44 are threaded together as indicated at 47. Obviously, the two sections 6 and 7 are capable 65 of swivel movement relative to each other,

there still remaining electrical connections at all times between the conductors 8 and 9, and 16 and 17.

Referring to Figure 6 it will be noted that the yieldable contact pins 31 and 32 are eliminated and in lieu thereof the conductors 8^a and 9^a have contact heads 8^b and 8^c, which engage with the contact ring 27 of the section 7 of the swivel and the contact head 26 of the conductor 17 of the section 7 of the swivel respectively. In Figure 6 the contact ring 27 is carried by the conductor 16. These contacts and conductors afford electrical connections between the wires 12 and 13, and 20 and 21 as shown in Figure 1.

In order to afford yieldable pressure between the contacts and yieldable action for the sections 6 and 7, expansion coil springs 50 and 51 are interposed between the ball bearing retaining rings 41 and 42 (which are reversed in position to those in Figure 2) and the shoulders 37^a and 38^a. In this instance the ball bearings engage with the flanges 45 and 46 of the sleeves.

Referring to Figure 10 it is to be noted that 90 the adjacent faces of the two sections of the swivel may be provided with three contact rings 52, 53 and 54, which together with the central contact head, there may be four electrical connections afforded. In this manner 95 most any number of electrical connections may be made. When using the four contact rings, they are connected to the conductors 55, 56 and 57, shown in dotted lines in Figure 10.

Referring to Figure 8 it will be noted that the swivel is adapted for use in connection with a screw plug, while in Figure 9 the swivel is adapted to use in connection with a push plug.

The invention having been set forth, what is claimed is:

1. In a swivel for two sections of a drop cord, the combination with two insulating sections, one socketed within the other, of means including anti-frictional elements for swivelly uniting the two insulating sections said means permitting movement of said sections toward and from each other, electrical conductors encased within the insulating sections, certain of said conductors provided with a stationary contact ring and a stationary head, other of said electrical conductors provided with movable contacts, one engaging with the contact ring and the other engaging with the contact head.

2. In a swivel for two sections of a drop cord, the combination with two insulating sections, one socketed within the other of axially aligned sleeves threaded together for swivelly uniting the two insulating sections in a manner to provide yieldable movement of said sections toward and from each other, said insulating sections having shoulders, the sleeves having abutment shoulders, anti-fric-

tional means between the two sets of shoulders, electrical conductors encased within the insulating sections, certain of said conductors provided with a stationary contact ring and
5 a stationary head, other of said conductors provided with movable contacts, one engaging with the contact ring and the other engaging with the contact head, the remote ends

of the conductors having sockets, and means passing through the insulating sections and 10 partially into the sockets for holding plugs in the sockets and retaining the conductors in position in the insulating sections.

In testimony whereof I affix my signature.

ELDON W. BALDWIN.
